C. W. CATHCART.

WIND-WHEEL.

No. 177,321.

Patented May 16, 1876.

UNITED STATES PATENT OFFICE.

CHARLES W. CATHCART, OF WESTVILLE, INDIANA.

IMPROVEMENT IN WIND-WHEELS.

Specification forming part of Letters Patent No. 177,321, dated May 16, 1876; application filed March 22, 1876.

To all whom it may concern:

Be it known that I, CHARLES W. CATHCART, of Westville, in the county of La Porte and State of Indiana, have invented certain Improvements in Windmills, of which the following is a specification:

This invention relates to that class of windmills in which the sails are pivoted in such manner that the pressure of the wind tends to swing them out of play, or edge to the breeze, while this tendency is resisted by reason of a weight so connected to the pivoted sails that the wind must be strong enough to overcome and raise the weight before the sails can turn out of the wind; and the invention particularly relates to the mechanism for connecting the weight to, and distributing its effect among, all of the sails equally.

In my improved mill I employ a series of radial sails, pivoted at one edge between two circular bands or rims, which form the wind-wheel. This large wheel is secured upon the end of an axial shaft, in the usual fashion of windmills. Loose upon this shaft, and in rear of the sails, is a second wheel, provided at its periphery with staples, which receive rods extended back—one from the free edge of each of the pivoted sails. The only motion of which this second wheel is capable, beyond the general rotation which it partakes in accompanying the great wheel, is a limited independent rotary motion, which is imparted to it from the sails or the weight at the moment of opening or closing the sails. It serves as a means of connection between all of the sails, causing them to move together. Upon the shaft, behind this second wheel, is the common grooved sliding collar, which is connected to the ordinary lever system, terminating in a weighted lever. The downward motion of the weight is contrived by means of the peculiar crank-connections, to cause the partial rotation of the second wheel, bringing the sails into the wind, and permitting, by its rotation in the opposite direction, the sails to be blown out of the wind. It is this peculiar mechanism of a second wheel, having a limited independent rotation, which, in connection with the pivoted sails, the method of attachment, and the mechanism for imparting or permitting the rotation, constitutes my

invention, and which will be better understood from the following detailed description, and the accompanying drawing, forming a part of this specification.

In the said drawing, Figure 1 is a side view of the mill, showing the sails full in the wind. Fig. 2 is a similar view with the sails turned out of the wind into planes parallel with its course. Fig. 3 is a perspective view of a portion of the wind-wheel, and of the second wheel and other parts, viewed from the rear.

Like letters of reference made use of in the several figures denote like parts wherever used.

The letter A upon the drawing marks the portion of the tower shown. B is the main shaft or axis of the wheel. The wheel itself, which carries the sails, consists, preferably, of two concentric bands or rims, C C', one of which, C, forms the periphery of the wind-wheel, and the other, C', of a less diameter, but standing in the same plane, serves as an enlarged hub. These bands are braced together, and to the real hub of the wheel, by suitable radial spokes. (Not anywhere shown in the drawing.) Between these bands, in the annular space, are placed the sails D, which are pivoted radially at one edge, having a bearing in both rims. The sails, thus mounted in the wheel, would be free, in the absence of any restraining power, to blow around each upon its pivot edge to the wind, as will be readily understood. They are, however, held to their work in the following manner: From the end nearest the hub of each sail is projected an arm, d, to the rear far enough to pass through staples or rings e in the wheel E, which I term the "second wheel." This wheel E is loose upon the main shaft, and stands in rear of, and near, the main or wind wheel, being of a diameter about equal to that of the rim C'. In rear of this second wheel, and also upon the shaft, is a sliding head, G, fitted with a groove and collar, g, slotted to receive the forked end of a bent lever, H, fulcrumed to the cap of the tower, and provided with an adjustable weight, J. Pivoted to the sliding head, and projecting to the front, are two joint-rods, L L, which join the head to the arms M M of two radial rock-shafts, N N, each journaled in the second wheel from rim to hub, and each having an

arm at its outer extremity O, extending forward and engaging a loop or staple upon the inner surface of the rim C'.

Now, it will be seen that the downward pressure of the weight J upon its lever tends to push forward the sliding head G, and, through the joint-rods L, to rock the shafts N, and to swing the arms O in opposite directions, thereby rotating the second wheel, or tending to rotate it, in such a direction that the sails will be swung upon their pivots into the position shown at Fig. 1 of the drawing. The force of the weight is, therefore, always applied to the sails to keep them in the wind, and they only depart from this position, and move upon their pivots, when the wind becomes strong enough to overcome the weight and raise it more or less.

In order to give a free motion to the parts the rods d, which connect the sails to the second wheel, are put on the sails at an angle of, perhaps, thirty degrees, so that they shall swing as far to one side of the sail-pivot as to the other in the operation of opening or closing the sails. This permits an easy, free motion of the rod through the staple, and obviates the difficulty of too much slant of the rod.

By this construction of the governing apparatus, and the employment of a second wheel, which does not slide upon the shaft, but simply rotates, with a limited independent rotation, all undue strain is prevented upon the various parts of the mechanism, and a quickly-sensitive government is insured.

My improved mill will attend to itself under almost all circumstances, requiring very

little watching, and, in a gale of wind, will present very little surface to catch the dangerous blast.

Having thus fully described the construction and operation of my invention, that which I claim as new, and desire to secure by Letters Patent, is—

1. The main or sail-carrying wheel, attached rigidly to the shaft, and bearing sails pivoted at one edge, in combination with a second wheel upon the same shaft, fixed at a certain distance from the main wheel, and having a limited independent rotation, induced or permitted by a weight, said second wheel being connected to the sails by means substantially as specified, so that it will operate the sails without sliding back and forth upon the shaft, all substantially as specified.

2. The combination and arrangement of the pivoted sails D, the second wheel E, the rock-shafts and arms L M N, and the sliding head G and weighted lever, substantially as specified.

3. The combination, with the weighted lever and sliding head, of the rock-shafts, and arms L M N, and second wheel E, all substantially as specified.

4. The combination of the pivoted sails and the second wheel, the sails being connected with the second wheel by rods d, placed at a dividing angle, and playing through eyes upon said second wheel, substantially as specified.

CHARLES W. CATHCART.
